UNITED STATES PATENT OFFICE.

HERBERT R. KEITHLEY, OF BUFFALO, NEW YORK.

DOOR-FASTENING FOR FREIGHT-CARS.

SPECIFICATION forming part of Letters Patent No. 712,309, dated October 28, 1902.

Application filed April 25, 1902. Serial No. 104,690. (No model.)

To all whom it may concern:

Be it known that I, HERBERT R. KEITHLEY, a citizen of the United States, residing at Buffalo, in the county of Erie and State of New York, have invented new and useful Improvements in Door-Fastenings for Freight-Cars, of which the following is a specification.

This invention relates to mechanism for operating the hopper-doors of hopper-bottom cars, and has for its object to provide a door-operating mechanism which is very simple in construction and comparatively light in weight of metal and which is efficient and convenient in operation.

15 In the accompanying drawings, consisting of two sheets, Figure 1 is a fragmentary side elevation of a hopper-bottom car, showing one of the hoppers of the car provided with my improved door-operating mechanism, the 20 door being shown closed. Fig. 2 is a horizontal section in line 2 2, Fig. 1. Fig. 3 is a side elevation of the door-operating mechanism, showing the door open. Fig. 4 is a bottom plan view of the parts shown in Fig. 1.

25 Like letters of reference refer to like parts in the several figures.

The body of the hopper-bottom car may be of any usual or desirable construction, that shown in the drawings having upright side 30 walls A, end walls B, and a bottom frame C, composed mainly of side sills c, end and cross sills c' c², and horizontal center sills c³. The inclined outer bottom plates D and intermediate bottom plates E extend with their lower 35 portions d e below the bottom frame and have these lower portions connected below the bottom frame by upright side walls f in the usual manner. The intermediate inclined bottom plate E is provided below the 40 bottom frame with the usual discharge-opening, which is closed by a door G of any suitable construction. The door is connected at its upper end by hinges g to the intermediate bottom plate E, so that the door swings 45 toward and from the lower end of the outer bottom plate D.

The mechanism for operating the door is constructed as follows: h represents a transverse rock-shaft, which is arranged beneath 50 the lower portion of the outer bottom plate D and journaled in bearings or straps h', secured to said plate at the sides of the car.

I represents arms which are secured to the rock-shaft h, near the ends thereof, outside of the bearings h' and extending on each side 55 of the car across the side of the hopper-tip and beyond the door when the latter is closed.

J represents a link which connects the free end of each rock-arm I with the door. This link is arranged on the inner side of the adjacent rock-arm I and connected with the latter by a pivot-bolt i and with the door by a pivot-bolt k, passing through a lug or hinge-strap k', secured to the door, Fig. 2.

L represents a stop which is secured to the 65 rock-shaft h on the outer side of the rock-arm I and which has above the shaft a stop-face l, against which engages a locking dog or pawl M. The two dogs on opposite sides 70 of the car are secured to a transverse rock-shaft m, so that both can be operated simultaneously from either side of the car. The stops L are preferably formed with hubs l', by which they are secured to the rock-shaft h. 75

n represents stop-shoulders arranged on the sides of the hopper-tip in such a position that the rock-arms rest upon these shoulders when the door is closed, as represented in Fig. 1. These shoulders are preferably formed 80 by castings, which are riveted to the hopper sides, as shown in the drawings.

o represents stiffening-bars of any suitable form secured to the lower side of the lower portion of the outer bottom plate D. 85

The rock-shaft h, to which the rock-arms I are secured, and the rock-shaft m, to which the dogs M are secured, are preferably made square throughout or partly for convenience in attaching the arms I and stops L to the shaft h and the dogs M to the shaft m, and so that a wrench or crank can be applied to the ends of said shafts.

When the door is closed, as represented in Figs. 1, 2, and 4, the rock-arms I rest upon 95 the stop-shoulders n at the sides of the hopper-tip, the links J stand in line with the rock-arms, and the dogs M bear against the faces of the stops L, whereby the door is prevented from opening under the pressure of the load. 100 For opening the door the dogs M are swung up out of the way of the stops L, when the load pressing on the door will open the same to the position shown in dotted lines in Fig.

1 and in full lines in Fig. 3, the rock-arms being swung upwardly by the opening movement of the door.

When there is not sufficient load in the car 5 to open the door freely, it can be opened by turning the rock-shaft *h* in the proper direction to swing the arms *I* upwardly.

I claim as my invention—

1. The combination of a hopper-bottom, a 10 hinged door arranged on one side of the same, a rock-arm fulcrumed on said bottom and extending beyond said door when the latter is closed, a link connecting the free end of said rock-arm with said door, and means whereby 15 said rock-arm is held in position for holding said door closed, substantially as set forth.

2. The combination of a hopper-bottom, a 20 hinged door arranged on one side of the same, a rock-arm fulcrumed on the opposite side of the bottom and extending beyond said door 25 when the latter is closed, a link connecting the free end of said rock-arm with said door, a stop connected with said rock-arm, and a locking device engaging said stop for holding the door closed, substantially as set forth.

3. The combination of a hopper-bottom, a 30 hinged door arranged on one side of the same, a rock-arm fulcrumed on the opposite side of the bottom and extending beyond said door 35 when the latter is closed, a link connecting the free end of said rock-arm with said door, a rock-shaft to which said rock-arm is secured, a stop secured to said rock-shaft, and a locking-dog adapted to engage said stop for holding the door closed, substantially as set forth.

4. The combination of a hopper-bottom, a 35 hinged door arranged on one side of the same, a rock-shaft fulcrumed on the opposite side

of the bottom, rock-arms secured to the ends of said rock-shaft and extending beyond said 40 door when the latter is closed, links connecting the free ends of said rock-arms with said door, a stop secured to said rock-shaft, a dog-shaft journaled on said bottom, and a dog secured to said shaft and adapted to engage 45 said stop for holding the door closed, substantially as set forth.

5. The combination of a hopper-bottom, a 50 hinged door arranged on one side of the same, a rock-arm fulcrumed on the opposite side of the bottom and extending beyond said door 55 when the latter is closed, a link connecting the free end of said rock-arm with said door, a stop-shoulder on the hopper-bottom for limiting the downward movement of said rock-arm, and means whereby said rock-arm is held in position for holding said door closed, substantially as set forth.

6. The combination of a hopper-bottom, a 60 hinged door arranged on one side of the same, a door-operating rock-shaft arranged on the opposite side of the bottom, rock-arms secured to said shaft and extending beyond said door, links connecting the free ends of said rock-arms with said door, stops connected with said 65 door-operating rock-shaft, a locking rock-shaft arranged near the latter, and locking-dogs secured to said locking rock-shaft and adapted to engage said stops for holding the door closed, substantially as set forth.

Witness my hand this 23d day of April, 1902.

HERBERT R. KEITHLEY.
